UNITED STATES PATENT OFFICE

141,135

DESIGN FOR A PORTABLE YARDER

Adolph Zwald, Portland, Oreg., assignor to Hyster
Company, Portland, Oreg., a corporation of Oregon

Application November 11, 1944, Serial No. 116,279

Term of patent 14 years

(Cl. D14—3)

To all whom it may concern:

Be it known that I, Adolph Zwald, a citizen of the United States and a resident of Portland, in the county of Multnomah, State of Oregon, have invented a new, original, and ornamental Design for a Portable Yarder, of which the following is a specification, reference being had to the accompanying drawings, forming a part thereof.

In the drawings:

The dominant features of my design are shown by means of full lines in the drawings.

I claim:

The ornamental design for a portable yarder, as shown and described.

ADOLPH ZWALD.
